STRAND MATERIALS DISPENSER OR THE LIKE

William S. Fortune, 14250 Dearborn St.,
Panorama City, Calif. 91402

Filed Jan. 2, 1973, Ser. No. 320,125

Term of patent 14 years

Int. Cl. D20—02

U.S. Cl. D9—193

Fig. 1

Fig. 2

FIG. 1 is a frontal perspective of a strand materials dispenser or the like showing my claimed design; and FIG. 2 is a rear perspective thereof.

The broken lines are shown for illustrative purposes only.

I claim:

The ornamental design for a strand materials dispenser or the like, substantially as shown and described.
